UNITED STATES PATENT OFFICE.

HERMANN ANSCHÜTZ-KAEMPFE, OF NEUMÜHLEN, NEAR KIEL, GERMANY.

METHOD OF GYROSCOPIC CONTROL.

1,180,365.

Specification of Letters Patent. Patented Apr. 25, 1916.

Application filed January 3, 1912. Serial No. 669,264.

To all whom it may concern:

Be it known that I, HERMANN ANSCHÜTZ-KAEMPFE, a subject of the Emperor of Germany, and a resident of Neumühlen, 5 near Kiel, Germany, Heikendorfer Weg 9, have invented certain new and useful Improvements in or Relating to a Method of Gyroscopic Control, of which the following is a specification.

- 10 The invention relates to an improved method of gyroscopic control for steering torpedoes, and to improvements in gyroscopic apparatus for carrying out such method.
- 15 The object of the invention is to decrease any initial angle of tilt of the gyroscope and to increase the resistivity or stability of the axle of the gyroscope. I accomplish this by speeding up or accelerating the rotation of the fly-wheel of the gyroscope after it has already been set in motion.

As a torpedo is leaving its tube the gyroscope, as a whole, is set in motion with its axle (axis of spin) fixed in a position parallel to the fore and aft center line of the torpedo. The starting mechanism is then withdrawn as well as the clamps which fix the axle of the gyroscope with reference to the torpedo. These operations are all completed before the torpedo has entirely left the tube. It is obvious that in this way the axis of spin tends to preserve its initial direction, *i. e.*, the direction of the tube at the moment of firing. If, just at this time, the 25 ship should roll, the tube, as a rule, will not be horizontal, but inclined as to the horizon, by angle which may amount to as much as 10° to 20°. Once in the water, the torpedo will take up a substantially horizontal course, whereas the axis of spin of the gyroscope will maintain its original position in space and have a certain angle of tilt with reference to the torpedo.

40 My invention will be better understood by referring to the accompanying drawings in which—

Figure 1 is a diagrammatic cross section through a torpedo in its tube in a rolling ship; Fig. 2 is a similar view of the torpedo (enlarged) while on its course; Fig. 3 is a diagrammatic perspective view of a gyroscope with horizontal axis arranged according to my invention; Fig. 4 is a view similar to Fig. 3, but showing the axle tilted up 45 as to the horizon; and Fig. 5 is a view, simi-

lar to Fig. 4, of a gyroscope of the original Obry type.

Referring to Fig. 1, this is a cross-section through a rolling ship *a*, having a torpedo tube *b* charged with a torpedo *c*, the axis *d* of the gyroscope *e* being in coincidence with the longer axis of the torpedo, but forming an angle α with the horizon; while Fig. 2 is a cross-section through the torpedo *c* during its course, showing the torpedo horizontal; the axis *d* of the gyroscope *e* is now tilted up through the same angle α with reference to the horizon and to the torpedo. If, while in its course, the gyroscope gradually loses its speed of rotation, as must be the case with gyroscopes of the usual Obry type, it is clear that the axis must tilt up further, *i. e.*, that the angle α must increase. The steering mechanism of the torpedo is set in action by the vertical gimbal ring *3*, which may be said to be "steadied" by the spinning gyroscope. All other conditions, alike, this vertical ring *3* is steadied best, when the axle of the fly-wheel *1* is horizontal. The resistive force will decrease inversely to the sine of the angle of tilt α . The greater the elevation, the less efficient the gyroscope for its purpose, until the axle becomes vertical and the steadyng power disappears altogether.

A second disadvantage of gyroscopes set in motion by a momentary impulse and then allowed to slow down (Obry type *e. g.*), lies in the fact that any small precessional movements about the vertical axis gradually become quicker. Klein and Sommerfeld in their standard work, p. 785, state substantially, that the fly-wheel must be centered with the utmost care so that its center of gravity will coincide exactly with the point of intersection of the axes of the outer and the inner ring, and that only thus will the momentum preserve its direction during the course. Otherwise the axis of spin will perform a more or less regular precession about a vertical line.

If a gyroscope be badly balanced, the path of the torpedo through the water, therefore, may follow a fairly straight line at first, but degenerate gradually into a curve.

In order to improve the Obry type, gyroscopes have been devised where an electric motor is used to keep up the rotation initially imparted by a spring motor or an

adequate contrivance. The object has been to attain the best results possible by keeping the number of revolutions as constant as possible during the entire course of the 5 torpedo.

In contra-distinction to such devices the present invention has for its purpose to improve the working of the gyroscope by increasing the initial velocity of spin during 10 a period extending over the whole or a good

part of the course of the torpedo. It is an essential feature of the invention that this increase of the rotational velocity or acceleration shall take place after the fly-wheel 15 has acquired its full freedom about its three mutually perpendicular axes and after all clamps or similar devices for locking it in a predetermined position with reference to the torpedo have been removed.

20 (1.) I provide, by my invention, that any angle of tilt, which the axis of the gyroscope may have had at the beginning of its course, shall be made smaller.

(2.) That any precession in azimuth of 25 the gyroscope shall become slower, since the steadyng moment of the gyroscope is increased, or, in other words, that the change of azimuth in a given time shall be made smaller. Thereby the certainty that the 30 torpedo will hit the mark is considerably increased, especially at long ranges. Since, according to the invention, the acceleration must be given to the fly-wheel after the liberation of the gyroscope, it is necessary that 35 the non-rotating part of the motor employed for the purpose be mounted in the inner gimbal ring.

The method of operation will now be explained with reference to Fig. 3 in which is 40 shown a fly-wheel 1, journaled in the gimbal ring 2, and a suitable electric motor 6, capable of rotating the fly-wheel 1, the stator of said motor being rigidly attached to ring 2, which ring 2 is journaled at 4-4 in a substantially vertical gimbal ring 3; a weight 45 12 serves as a counterpoise for the motor 6. Gimbal ring 3 is carried rotatably at 5-5 by two suitable bearings which are fixed with reference to the torpedo proper. As 50 various methods of steering the torpedo according to the apparent motions of ring 3 about axis 5-5 are well known and as these methods do not form part of this invention, the respective appurtenances, including 55 motor connections, are omitted in the drawing for clearness sake. A small toothed pinion 13 is mounted on the shaft of the fly-wheel in mesh with wheel 14 driven by motor 15, preferably a spring motor. At 60 the moment of firing the torpedo, motor 15 is automatically started and fly-wheel 1 put in operation. Immediately thereupon this motor 15 and wheel 14 are slid back so as to clear wheel 13, thus permitting free motions 65 of said wheel 1 in every direction. Motor 6

is now started and given sufficient electric current to increase the number of revolutions according to the invention. A simple and efficient means to perform this consists in driving the supply generator by the propeller shafts, as these shafts are set in motion only after the liberation of the gyroscope. 70

Fig. 4 repeats the essential parts of Fig. 1, but shows an angle of tilt for the gyroscope axis. 75

Fig. 5 shows, diagrammatically, a gyroscope of the original Obry type having an angle of tilt for the gyroscope axis of spin.

I will now explain in which way the acceleration of the gyroscope wheel causes the 80 angle of tilt to be reduced.

The motor 6 exercises a torque on the fly-wheel 1, as indicated by arrow 8. As long as the rotation of the fly-wheel is accelerated, the rotor of motor 6 exercises an opposite 85 torque on the stator, as indicated by arrow 9. In Fig. 1 this torque lies accurately in a plane parallel to ring 3 and is consequently entirely taken up by the bearings 4.

In Fig. 4 the axle of the fly-wheel assumes 90 the direction of $o-z'$, having, therefore, an angle of tilt with the horizon.

The reaction torque 9 of the motor, the total amount of which may be called D, must be considered as a compound torque 95 with regard to the two gimbal rings 2 and 3. The respective components are $D \cos \alpha$, acting about axis $o-z$, and $D \sin \alpha$ acting about axis $o-w$. The first component $D \cos \alpha$ is neutralized by the bearings 5-5. 100

It follows from the well known laws of gyroscopic motion that under the influence of the turning couple $D \sin \alpha$ ring 3 will not alter its position, but that the axle of the fly-wheel is brought nearer the normal position $o-z$. As stated above, the steadyng power of the gyroscope is thus always fully utilized. 105

In Fig. 5 a gyroscope, spinning as shown by arrows 8 is represented which, during the course of the torpedo, is not motor driven. The friction in the bearings of the fly-wheel will tend to drag around with it the inner gimbal ring 2. Consequently, a compound torque 11-11 acts on ring 2 in the same 110 sense as the normal spin, and this may, similarly be resolved into two components $D \cos \alpha$ and $D \sin \alpha$. The component $D \sin \alpha$, acting here in the opposite sense as in Fig. 2, 115 has, according to the laws of gyroscopic motion, a contrary effect, *i. e.*, it tends to increase the angle α . It is worth noticing, that the magnitude of the turning couple, $D \sin \alpha$, depends on the magnitude of the angle α . Thus a small angle will increase at 120 first very slowly, but gradually faster and faster, and in some cases, at long ranges, may even reach the limit of 90° . 125

From the above considerations it will be 130 understood that for the correct operation of

- my device it is imperative that the stationary part of the motor 6 be fixed to the inner cardanic ring so as to participate in the angular movement of the axle of the fly-wheel.
5. Having described my invention, I claim:
1. In torpedoes adapted for ejection from a torpedo tube and provided with a rotatory, cardanically suspended wheel, the method of control which comprises rotating the wheel at a predetermined speed while the torpedo is being ejected and while the gyroscope and torpedo are fixedly locked together, and in subsequently after the gyroscope is unlocked materially increasing the speed of rotation of the wheel electrically, for the purpose specified.
  2. In torpedoes adapted for ejection from a torpedo tube and provided with a rotatory cardanically suspended wheel, the method of control which comprises mechanically rotating the wheel at a constant speed as the torpedo is being ejected and while the gyroscope and torpedo are fixedly locked together, and in subsequently after the gyroscope is unlocked materially increasing the speed of rotation of the wheel electrically for a predetermined time, for the purpose specified.
  3. In torpedoes adapted for ejection from a torpedo tube and provided with a rotatory, cardanically suspended wheel, the method of control which comprises rotating said wheel at a predetermined speed as the torpedo is being ejected and while the gyroscope and torpedo are fixedly locked together after the gyroscope is unlocked increasing the speed of said wheel for the purpose described.
  4. In torpedoes adapted for ejection from a torpedo tube and provided with a rotatory, cardanically suspended wheel, the method of control which comprises rotating said wheel at a uniform speed as the torpedo is being ejected and while the gyroscope and torpedo are fixedly locked together after the
- gyroscope is unlocked accelerating the speed of said wheel.
5. In torpedoes adapted for ejection from a torpedo tube and provided with a rotatory, cardanically suspended wheel locked to the torpedo, the method of control which comprises rotating the wheel at a predetermined speed while the torpedo is being ejected, then unlocking the gyroscope and in then increasing the torque of the wheel while simultaneously applying a torque in the opposite direction to the ring in which said wheel is pivoted.
6. In torpedoes adapted for ejection from a torpedo tube and provided with a rotatory, cardanically suspended wheel locked to the torpedo, the method of control which comprises rotating the wheel at a predetermined speed while the torpedo is being ejected, then unlocking the gyroscope and in then increasing the torque of the wheel while simultaneously applying a torque in the opposite direction to the ring in which said wheel is pivoted and in gradually increasing both of said last named torques during the course of the torpedo.
7. In gyroscopes used for steering torpedoes driving mechanism which comprises a spring motor set in motion at the firing of the torpedo to rotate the fly-wheel and withdrawn when the axle of the gyroscope is unlocked and an electric motor, carried by the same frame as the fly-wheel, for accelerating the rate of spin of the fly-wheel after its axle is unlocked during the whole or a good part of the course of the torpedo, for the purpose specified.
- In witness whereof I have hereunto signed my name this 12th day of December, 1911, in the presence of two subscribing witnesses.
